UNITED STATES PATENT OFFICE.

DAVID T. SHARPLES AND GERALD D. GROSNER, OF WEST CHESTER, PENNSYLVANIA,
ASSIGNORS TO THE SHARPLES SPECIALTY COMPANY, OF WEST CHESTER, PENN-
SYLVANIA, A CORPORATION OF DELAWARE.

BEARING.

1,401,195.

Specification of Letters Patent. Patented Dec. 27, 1921.

Application filed April 25, 1919. Serial No. 292,559.

To all whom it may concern:

Be it known that we, DAVID T. SHARPLES and GERALD D. GROSNER, both citizens of the United States, and residents of West Chester, in the county of Chester and State of Pennsylvania, have jointly invented certain Improvements in Bearings, of which the following is a specification.

Our invention is designed primarily for 10 the purpose of eliminating the objectionable effects on bearings of the actions of certain spindles having an inherent tendency to lateral, wabbling and longitudinal movements, such as spindles for suspending and revolving 15 the bowls of centrifugal separators, but it will be understood that it is not limited to such special use.

The improvements of our invention comprise essentially a combination in which an 20 elastic flange coupling is interposed between the spindle and the bearings through which such spindle is supported and revolved.

In the preferred form of our improvements as it has been applied heretofore, the 25 vertical shaft which carries and revolves the separator bowl extends freely through a stationary bearing which carries a prime mover through anti-friction bearings, the prime mover supporting and driving the 30 spindle through the flexible device.

The characteristic features of our improvements are fully set out in the following description and the accompanying drawings in illustration thereof.

35 In the drawings, Figure 1 illustrates a broken vertical sectional view of a centrifugal separator having a bowl suspended by a spindle to which our improvements are applied; Fig. 2 is an enlarged vertical sectional view of the improved bearing; Fig. 3 is a sectional view taken on the line 3^x—3^x of Fig. 2; Fig. 4 is a vertical sectional view in illustration of a modified form of the bearing, Fig. 5 is a sectional view taken on the line 5^x—5^x of Fig. 4, and Fig. 6 is a vertical sectional view of a further modification.

50 The invention as embodied by the mechanism illustrated in Figs. 1, 2 and 3, comprises the support or frame 1 provided with the member 1¹ having screwed in its top the sleeve 2 through which passes freely the

spindle 3 for suspending and revolving the bowl 4.

Bearing rings 5, provided with the concentric external annular channels 5¹, are fixed on the upwardly projecting tubular extension 2¹ of the sleeve 2; the upper part of the extension being reduced with the provision of a shoulder 2¹¹ on which the lower 55 ring 5 bears, a spacing ring 6 being sleeved on such part with the provision of bearings for such rings, and a nut 7 being screwed on the top of the extension into engagement with the upper ring 5 to hold the several 60 rings in place.

A pulley 8, which has been placed on the extension 2¹ previously to the application thereto of the specified rings, contains the rings 9 provided with the internal circular races 9¹ concentric with the respective races 5¹, balls 10 being disposed in the complementary races of such rings 5 and 9. The rings 9 are fixed in a sleeve 11 which is disposed within the pulley 8, this sleeve having 70 an internal bearing member 11¹ surrounding the ring 6, for spacing the rings 9 and holding 75 them in place.

A recessed cap 12 having an open top is 80 set in the top of the pulley 8 in close proximity to the top of the upper ring 9 and the sleeve 11, the nut 7 lying within the cap.

The cap 12 is provided with the internal flange 12¹ and contains a felt ring 13 which rests on such flange, the ring being held in 85 place by a stud 14 screwed radially through the cap and penetrating the ring. The spindle 3, which extends through the parts 12¹ and 13 within the cap 12, has a bearing ring 15 fixed on the top thereof by a screw 16, 90 this ring being in free relation to the cap and having a stud 17 set therein and extending into the felt ring 13.

A duct 12¹¹ extends through the cap 12 to supply a lubricant to the bearing members 95 in the pulley 8, which has a well 8¹ in the bottom thereof for holding oil when the pulley 8 is at rest.

It will be understood that the weight of the bowl 4 is carried by the spindle 3 to the 100 frame 1 through the members described and that the revolution of the bowl through the application of force as by the belt 18 on the pulley 8 transmits power through the elastic

ring 13 which permits limited movement of the spindle and bowl laterally, angularly and longitudinally without the transmission of such irregular movements to the pulley 5 and the anti-friction bearings.

In the form of the apparatus illustrated in Figs. 4 and 5, a coiled spring 19 is substituted for the felt ring 13, one end of the spring being fixed by a stud 20 to the cap 10 12 and the other end of the spring being connected by a stud 21 to the ring 15. In this form of the device, the spring neutralizes the effects otherwise communicated to the anti-friction bearings through the pulley.

15 In the form of the apparatus illustrated in Fig. 6, the elastic ring or washer 13¹ is secured to the flange 12¹ of the cap 12 by the screws 14¹ having their heads sunk below the top of the washer. The spindle 3 20 is connected to the washer frictionally by direct engagement therewith and by the ring 15¹ which engages the top of such washer, the ring being secured to the spindle by the screw 16¹ having the annular flange 16¹¹ 25 sleeved on the spindle and engaging the ring in wedging relation. Here the frame member 1¹ is provided with the guard 1^a for the pulley 8.

Having described our invention, we claim:

30 1. The combination with a support and a vertical spindle, of mechanism comprising anti-friction bearings and elastic means whereby said spindle is suspended and revolved with relation to said support, said 35 elastic means comprising a fibrous bearing member interposed between said bearings and spindle and adapted for modifying the effect on said bearings of irregular actions of said spindle.

40 2. The combination with a support and a

spindle, of mechanism whereby said spindle is suspended and revolved in relation to said support, said mechanism comprising a race ring carried by said support, a race ring concentric with the race ring aforesaid, 45 means for connecting said second named race ring with said spindle, anti-friction devices engaged in the complementary races of the rings aforesaid, and driving means comprising a pliable member through which 50 power is transmitted to said spindle.

3. The combination of a frame, a sleeve detachably connected with said frame, a spindle revoluble in said sleeve, a ring having an exterior circular race mounted on said 55 sleeve, a ring having an interior circular race surrounding said ring first named, anti-friction devices engaged in said races, and mechanism comprising elastic means adapted for connecting said second named 60 ring with said spindle and driving means acting through said elastic means on said spindle.

4. The combination of a frame, a sleeve detachably connected with said frame, a 65 plurality of rings having external races fixed to said sleeve, a plurality of rings having internal races surrounding respective rings aforesaid, anti-friction devices engaged in complementary races aforesaid, driving 70 means fixed to said second named rings, a spindle extending through said sleeve and elastic means connecting said driving means with said spindle whereby irregular movements of said spindle are absorbed. 75

In testimony whereof we have hereunto set our names this 21st day of April, 1919.

DAVID T. SHARPLES.
GERALD D. GROSNER.
